UNITED STATES PATENT OFFICE.

HAROLD F. SHAW, OF LEOMINSTER, MASSACHUSETTS.

DESIGN FOR A COMBINED FRAME AND BODY WITH HOOD FOR A BABY CARRIAGE.

Application filed October 14, 1926. Serial No. 19,354. Term of patent 7 years.

To all whom it may concern:

Be it known that I, HAROLD F. SHAW, a citizen of the United States, residing at Leominster, county of Worcester, and State of Massachusetts, have invented a new, original, and ornamental Design for Combined Frame and Body with Hood for a Baby Carriage, of which the following is a specification, reference being had to the accompanying drawing, forming part thereof.

The figure is a perspective view of the frame, body and hood of a baby carriage showing my new design, running gear such as might be utilized to support the same being indicated in dotted lines.

I claim:—

The ornamental design for a combined frame and body with hood for a baby carriage, as shown.

HAROLD F. SHAW.
